The ornamental design for a ground-engaging support head for a line trimmer, as illustrated and described.

DESCRIPTION

FIG. 1 is a front top perspective view of a first embodiment of my new design for a ground-engaging support head for a line trimmer;

FIG. 2 is a front top perspective view thereof, with the drive head of the line trimmer removed;

FIG. 3 is a front bottom perspective view thereof;

FIG. 4 is a top plan view thereof;

FIG. 5 is a bottom plan view thereof;

FIG. 6 is a front elevation view thereof;

FIG. 7 is a rear elevation view thereof;

FIG. 8 is a left side elevation view thereof;

FIG. 9 is a right side elevation view thereof;

FIG. 10 is a front top perspective view of a second embodiment of my new design for a ground-engaging support head for a line trimmer;

FIG. 11 is a front bottom perspective view thereof;

FIG. 12 is a top plan view thereof;

FIG. 13 is a bottom plan view thereof; and,

FIG. 14 is a side elevation view thereof.

The broken lines showing a line trimmer drive head, a line reel assembly; drive head receiving sockets and associated line segments are included for showing unclaimed subject matter and form no part of the claimed design.
